UNITED STATES PATENT OFFICE.

IDA C. MACKEOWN, OF NEW YORK, N. Y., ASSIGNOR TO HELEN P. SINGER CO., INC., OF NEW YORK, N. Y., A CORPORATION OF NEW YORK.

DOLL.

1,315,378.

Specification of Letters Patent. Patented Sept. 9, 1919.

Application filed February 28, 1919. Serial No. 279,762.

To all whom it may concern:

Be it known that I, IDA C. MACKEOWN, a citizen of the United States, residing at New York city, in the county of New York and 5 State of New York, have invented a certain new and useful Improvement in Dolls, of which the following is a specification.

The present invention relates to an improvement in dolls.

10 It is well known that the prices of artistic and daintily gotten up dolls which are constructed to resemble as nearly as possible a beautiful and prettily dressed girl have of late years become so excessive that the 15 poorer classes of people have been compelled to purchase for their little ones cheap substitutes, which are more or less monstrosities in appearance and can serve no useful purpose in the esthetic education of 20 the child, even though they may afford it some amusement. It is believed that dolls should serve the purpose of aiding in creating in a child a taste for neatness, dainty arrangement of clothing and attractive 25 appearance, as well as to develop and administer to the child's motherly instincts. Ugly and unhuman looking dolls cannot accomplish this purpose. It is the object of the 30 present invention to produce a doll which shall be neat and attractive in appearance, having a face and other parts strongly suggesting a pretty child, and which shall be strong and durable and yet cheap and economical to manufacture, so that it may be 35 sold at a reasonable price and thereby be within the purchasing power of poor families. This object is accomplished in the improved doll hereinafter described and particularly pointed out in the appended claims.

40 In the accompanying drawings illustrating the preferred form of the invention, Figure 1 is a front elevation of the completed doll; Fig. 2 is a sectional side elevation of the head, showing the manner of attaching the imitation hair thereto, Fig. 3 is a detail showing the manner of attaching the imitation hair to the skull-piece; Fig. 4 is a perspective of the doll's head with the hat on; and Fig. 5 is a perspective of the 45 doll's head showing the arrangement of the imitation hair without either ribbon or hat.

In constructing or making up the doll illustrated in the drawings, I first secure a 50 hollow head piece 7, the face portion of which is formed to resemble as nearly as possible the contour of the face of a pretty girl child, with the cheeks stained and the eyes, eye-lids and eye-brows painted in the requisite colors, depending on whether the doll is to be of the blonde or brunette variety, and with the nostril openings and the lips properly tinted. Doll heads like this are cheaply manufactured and can be purchased in the open market, and are far more 55 human-like in appearance than rag or knitted doll heads. Having fixed painted eyes rather than glass eyes or eyes like the so-called "sleeping" dolls, does not in the least spoil the attractiveness or the prettiness of the doll face. This hollow doll head piece 60 is composed of a composition material adapted to withstand much abuse without breaking. The hollow head piece is provided with a flaring portion at the breast 65 and the back part 9 of the shoulders, which 70 will not only serve the purpose of a bosom and shoulders presenting a comely appearance when a low-necked dress is on the doll, but which will also provide a sufficient support for the upper part of the torso or body 75 portion of the doll. This body portion may be composed of a fabric exterior compactly filled with a more or less resilient material, such as ground cork; such body portions may be purchased ready made. It is required 80 that the filling of the body portion of the doll be such that it will not become misshapen with much handling.

The arms 10 of the doll are preferably 85 composed of the same composition material as the head and are adapted to withstand considerable strain without breaking. The arms are prettily formed and are made bent, so that the forearms naturally project slightly forward when the upper portions of the arms lie parallel with the body. The arms are so joined to the body portion that they are permitted to 90 swing in a line parallel with the side of the body, as indicated in Fig. 1. The legs 11 of the doll are preferably composed of a fabric material and are stuffed with some such filling as cork or other material which will not readily lump and distort the shape 95 of the legs. The legs are joined to the torso in such fashion that they are capable of swinging. This may be effected by means of rivets backed by washers. This construction is such that it is practically impossible with ordinary usage for the legs 100

105

110

to become detached from the body portion of the doll. The fabric of which the legs are composed is preferably flesh colored, which is also the color of the arms.

5 In order to promote its artistic appearance and to make it resemble as nearly as possible a girl, the doll is provided with imitation hair. This imitation hair is composed of some textile material, preferably 10 strands of yarn or worsted of a color corresponding to the color of the eyes, that is to say, if the doll is to resemble a brunette, the yarn or worsted will be dark in color, such as brown or black, and if the doll is to 15 resemble a blonde or a fair person, the yarn or worsted will be light in color, such as yellow. A bunch 13 of these strands is fastened at their middle point 14, then sewn to a piece of fabric 15 called a skull-piece. The 20 skull-piece is next glued or otherwise securely attached to the head, as shown in Fig. 2. When this is done, the yarn is spread out on the head radiatingly, the point at which the strands of yarn are bound being substantially 25 the center of the top of the back portion of the head, which corresponds substantially to the point on the human head where the hair radiates.

The method of attaching the strands of 30 yarn to the skull-piece is indicated in Fig. 3. It is accomplished by holding up one end of the bunch of yarn strands and spreading the other end out over the skull-piece, and then sewing the yarn strands at their 35 middle point to the skull-piece. Care is taken that the sewing will not take in strands of the upper part of the bunch. When the strands of the upper end of the bunch are then spread out, they completely hide the 40 sewing stitches, and superficially it is impossible to tell how the imitation hair of the doll is fastened to its head. This construction is such that dolls with unpierceable heads may be provided with imitation hair 45 of textile material without gluing the hair directly to the doll's head.

The length of the strands of yarn is preferably such that the back portion of the imitation hair comes down to the shoulders of 50 the doll. The part thereof which extends toward the front and over the face is clipped at the forehead to resemble bangs, with the result that the face of the doll is prettily surrounded by its hair. When the hair has 55 thus been arranged on the doll, it may be kept in place by a small ribbon, with the bow showing at some point over the forehead to present as attractive an appearance as possible. A peculiar feature of importance involved in making the imitation hair 60 of the doll in this manner and in thus attaching it to the head of the doll is that all the strands of the yarn or worsted being attached to the head at only one point, the 65 child playing with the doll is afforded every

facility for arranging the doll's hair as it sees fit, if the primary arrangement does not satisfy it. Although the arrangement shown may be the best and most attractive, it is desirable for affording the child amusement in playing with the doll to attach the hair in this manner, so that the child may comb it, brush it, braid it and work upon it to its heart's content without injuring it.

Having constructed the doll as thus described, and it will be recognized that this construction is cheaply and economically accomplished, there being no expensive materials used in the work, and the shape and arrangement of the parts being such that 70 they are readily and quickly put together, and when so put together are strong and durable and capable of withstanding the ordinary strains to which dolls are subjected by the children playing with them 75 without the members falling apart, the doll is next dressed. The feet and lower portions of the legs are provided with half socks 16, so as to expose a short portion 17 of the flesh colored leg, and on the feet 80 are placed imitation kid slippers 18. The doll is next provided with a one-piece slip or empire gown 19, which may be cheaply 85 constructed and which when in place serves to give the doll the effect of being very tastefully and neatly dressed. On the head is placed a bonnet 20, in such fashion that the free ends of the imitation hair will project therefrom, the effect being very chic and 90 fascinating to the girl owner of the doll. 100 The imitation hair, instead of being short and arranged more or less like the fashion of dressing children's hair called the "Dutch clip," may be otherwise arranged. The principle of attaching the imitation hair to the doll's head, however, will not be departed from whatever the length or the material of which the imitation hair is composed. This principle is to secure imitation hair to 105 a doll's head which is composed of some hard unpierceable material, so that the hair strands will not be attached for any substantial part of their length to the head, but each strand will be free from the head except 110 at one point.

Having thus described the invention, what is claimed is:

1. A doll having a body portion with arms and legs attached thereto, a hard head piece secured to the body portion, a skull piece secured to the head piece, and imitation hair composed of strands of textile material attached to the skull piece at one point in such manner that the strands radiate from that point.
2. A doll having a body portion with arms and legs attached thereto, a hard head piece secured to the body portion, a skull piece secured to the head piece, and imitation hair composed of separate strands at-

tached at their middle point to the head piece so that half the strands are spread over the skull piece and the other half are spread over the first half so as to cover up the point
5 at which the strands are attached to the skull piece.
3. A doll having a body portion with arms and legs secured thereto, a hard head piece secured to the body portion, and imitation hair for the head piece composed of strands of textile material bound together at their middle point, a skull piece secured to the head piece and to which the strands are attached at their middle point, one-half
10 of the strands being spread out over the
15

skull piece before they are attached to the skull piece and the other half of the strands being spread out over the first half after they are attached to the skull piece.

4. A doll having a body portion with 20 arms and legs attached thereto, a hard head piece secured to the body portion, a skull piece secured to the head piece, and imitation hair composed of separate strands attached to the skull piece at one point and in 25 such manner that the strands radiate from that point and the uppermost strands cover up the point of attachment to the skull piece.

IDA C. MACKEOWN.
